Patented Aug. 11, 1970

218,316

TAPE DUPLICATING MACHINE

Joseph C. Bouzaglou, Sherman Oaks, and Alwin P. Schmid, Hollywood, Calif., assignors to Coast Export Co., Inc., a corporation of California

Filed June 3, 1969, Ser. No. 17,485

Term of patent 14 years

Int. Cl. D14—01

U.S. Cl. D26—14

FIG. 1

FIG. 2

FIG. 3

FIG. 4

FIG. 5

FIG. 1 is a perspective view of a tape duplicating machine showing our new design;

FIG. 2 is a side elevational view thereof on a reduced scale showing the side not visible in FIG. 1;

FIG. 3 is a rear elevational view thereof;

FIG. 4 is a top plan view thereof; and

FIG. 5 is a bottom plan view thereof.

We claim:

The ornamental design for a tape duplicating machine, substantially as shown.
